Patented Aug. 25, 1914.

UNITED STATES PATENT OFFICE.

JOHN WEBB, OF CHICAGO, ILLINOIS.

HINGE FOR TILTING SASH.

1,108,857.

Specification of Letters Patent. Patented Aug. 25, 1914.

Application filed August 27, 1913. Serial No. 786,859.

To all whom it may concern:

Be it known that I, JOHN WEBB, a citizen of the United States, residing at Chicago, in the county of Cook and State of Illinois, 5 have invented certain new and useful Improvements in Hinges for Tilting Sash, of which the following is a specification.

In tilting sash and particularly in that type adapted to close automatically to prevent the spreading of fire it is usual to provide a stop for limiting the angular swing of the sash and many forms of construction have been suggested for this purpose. Where the frame and sash are made of metal; 10 however, such stop, if formed as an integral part of the window construction, as a lip or an offset therefrom, is of insufficient rigidity and strength and is often associated with a weakening of the frame or sash.

The objects of the present invention are to provide a stop construction of great rigidity and strength, unyielding and not subject to malformation or other injury by the rough usage to which the stops are subjected in the hasty or careless opening and in the violent closing of such windows as when in case of fire or other emergency the retaining means is released and the sash allowed to slam to a closed position. Preferably, with these objects in view, the stop is 20 independent of the frame or sash, is firmly attached thereto, and is of heavy solid construction such as cast metal, serving the function of and assisting to close the sash by its own weight as well as to limit the 25 opening and closing movement and to relieve the window of the jar incident thereto.

In the accompanying drawing and in the description based thereon are set forth preferred and modified embodiments of the invention. As, however, the same is capable 30 of embodiment in other and varied constructional forms the drawing and description are to be construed in an illustrative sense and not as unnecessarily limiting the invention.

In the drawing: Figure 1 is a front elevation of a fragment of a window frame and sash provided with the improved stop device; Fig. 2 is a vertical section on the line 2—2 of Fig. 1; Fig. 3 is a transverse section on the line 3—3 of Fig. 1; Fig. 4 is a detail in perspective showing the trunnion device

common to both forms of the invention; Fig. 5 is a vertical section showing a modified form of stop; and Fig. 6 is a transverse section on the line 6—6 of Fig. 5.

Herein the reference numeral 11 designates generally a hollow sheet metal window frame, and 12 indicates in the same general manner a tilting sash mounted within the frame. Upon the front face of the frame is suitably secured a cast metal plate 13 having a portion 14 which serves as a journal bearing, the plate being secured to the front of the frame by means of screw headed bolts 15, 15 which extend through the front wall of the frame and also through a reinforcing cast metal plate 16 mounted within the frame against the front wall thereof. The plates 13 and 16 being securely clamped in assembled relation with each other and with the front wall of the frame by means of nuts 17, 17 threaded upon the inner ends of the bolts 15.

A trunnion plate 18 is firmly mounted upon the front face of each side of the sash 12 by means of screws 19 passing through the front wall of the sash into engagement with a filler block 20 within the sash. The screw holes in the trunnion plate are formed as elongated slots 21 which provide for vertical adjustment of the sash to fit correctly within the frame. The plate 18 has cast as an integral part thereof a trunnion 22 having a cylindrical journal 23 adapted to fit within the journal bearing 14 and also having beyond the cylindrical portion a squared portion 24 and beyond that a reduced threaded portion 25 to receive the nut 26. The end face of the trunnion is flattened at 27 in order to facilitate the adjustment of the same within a lathe for truing the journal portion 23. Immediately alongside the plate 13, the front wall of the window frame 11, and also the reinforcing plate 16 are slotted at 28, the slot 28 lying in a plane with the squared portion 24 of the trunnion.

A stop arm 29 has at one end a square opening by means of which it is mounted upon the squared portion 24 of the trunnion so as to be firmly fixed against relative angular movement and to swing with the sash in the tilting of the latter. Throughout the greater portion of its length the arm is flattened or narrow as shown at 30, while the

terminal portion of the arm is provided with a broad flat face 31 lying in a plane at substantially right angles to the plane of the narrow portion 30 and adapted to engage 5 against the rear wall of the frame in contact with the rear face of the reinforcing plate 16 as shown in dotted lines in Fig. 2 when the sash is in its tilted position, the arm occupying the position shown in full 10 lines in said figure when the sash is in its closed position. It will be observed that the narrow portion 30 of the arm plays within the slot 28 and the plane of this portion is parallel to the plane of movement of the 15 sash, while the plane of the broad flattened portion 31 is at right angles to the plane of the sash movement. The arm 29 is of cast metal and has considerable weight which assists in the closing movement of the sash. 20 The effective weight of the arm may be advantageously augmented by providing therein an opening 32 and suspending therefrom a weight 33. The point of pivotal support of the sash being off the center the sash will 25 tend to close of its own weight and this tendency is assisted by the weight of the arm 29 and of the weight 33.

In its closed position the joint between 30 the frame and sash is bridged above the pivotal point by the overlapping portion 34 of the sash, and below by the overlapping portion 35 of the frame. These overlapping portions would themselves act as stops to limit the closing movement of the sash, but 35 being of sheet metal are insufficient to long withstand the jar of the closing sash and serve in the present case rather as means for closing the joint between the sash and frame than as stops.

40 In Figs. 5 and 6 are shown modifications of construction in which the cast arm 29 previously described is replaced by a sheet metal arm 36 in the nature of a wing which plays within the narrow slot 37 and is at its 45 rear end angularly bent to one side at 38 and upon the opposite side has suitably secured thereto an angular portion 39 which together present a broad face adapted to impinge against the rear face of the reinforcing plate 16 in the tilted position of the sash, the parts 38 and 39 serving together a function similar to that of the broadened portion 31 of the previous construction. The arm in the present case may likewise be provided with a supplemental weight although 55 by reason of the mounting of the sash off its center the closing movement will be effected independently of the arm.

I claim:

60 1. The combination with a stationary member, a journal bearing mounted thereon, a tilting member, and a trunnion mounted on the latter and journaled within the bearing, of an arm mounted on the trunnion and 65 extending behind the stationary member and

adapted to engage the same to limit the swing of the tilting member, substantially as described.

2. The combination with a hollow stationary member having a slot in its front wall, journal bearings mounted thereon, a tilting member, and a pair of trunnions mounted on the latter and journaled within the bearings, of an arm mounted on one of the trunnions and extending through the slot into the stationary member and adapted to engage behind the front wall of the same to limit the swing of the tilting member, substantially as described. 70

3. The combination with a hollow stationary member having a slot in its front wall, journal bearings mounted thereon, a tilting member, and a pair of trunnions mounted on the latter and journaled within the bearings, of an arm mounted on one of the trunnions and extending through the slot into the stationary member and adapted to engage behind the front wall of the same to limit the swing of the tilting member, the arm having a narrow portion playing within the slot and a broad terminal portion to engage the rear wall of the member, substantially as described. 80

4. The combination with a hollow stationary member having a slot in its front wall, journal bearings mounted thereon, a tilting member, and a pair of trunnions mounted on the latter and journaled within the bearings, of an arm mounted on one of the trunnions and extending through the slot into the stationary member and adapted to engage behind the front wall of the same to limit the swing of the tilting member, the arm having a narrow portion playing within the slot and a broad terminal portion to engage the rear wall of the member, the two portions of the arm lying in planes at substantially right angles to each other, the narrow portion parallel to the plane of the tilting movement and the broad portion at right angles thereto, substantially as described. 90

5. The combination with a stationary member, journal bearings mounted thereon, a tilting member, and trunnions mounted on the latter and journaled within the bearings, of an arm mounted on one of the trunnions and extending behind the stationary member and adapted to engage the same to limit the swing of the tilting member, and a weight carried by the arm to assist in the return movement of the tilting member, substantially as described. 110

6. The combination with a hollow sheet metal frame having a slot in its front wall, a pair of journal bearings mounted thereon, a tilting sash, and a pair of trunnions mounted on the latter and journaled within the bearings, of an arm mounted on one of the trunnions and extending through the 120

slot into the frame and adapted to engage behind the front wall of the same to limit the swing of the sash, the arm having a narrow portion playing within the slot and a broad terminal portion to engage the rear face of the front wall of the frame, the two portions of the arm lying in planes at substantially right angles to each other, the narrow portion parallel to the plane of tilting movement and the broad portion at

right angles thereto, and a weight carried by the arm to assist in the return movement of the sash, substantially as described.

In testimony whereof I have hereunto signed my name in the presence of two subscribing witnesses.

JOHN WEBB.
